PRECIOUS METAL TRAP

Cayetano J. Apablaza, Los Angeles, Calif.

Application September 19, 1934, Serial No. 744,744

8 Claims. (Cl. 209—201)

This invention is a precious metal trap for use in association with dental cuspidors.

One of the objects of the invention is to provide a simple and inexpensive precious metal recovery device, which may be constructed as an independent unit, and in such manner that it may be employed with a standard type dental cuspidor, so as to operate in conjunction therewith. A further object is to equip a device of the character mentioned with means for baffling and straining those fluids of a character which are normally deposited into dental cuspidors, and to act upon such fluids in such manner as to separate the solids from the liquids, and to subsequently effect amalgamation of said solids with commercial mercury. A further object is to provide a precious metal trap formed of sections which may be readily assembled or separated, as occasion may require, so that the interior thereof is readily accessible for removal of its contents and for cleansing purposes, the device including means for normally maintaining the parts in assembled relation while in use.

The invention will be hereinafter fully set forth and particularly pointed out in the claims.

In the accompanying drawing:

Fig. 1 is a vertical elevation illustrating a precious metal trap unit constructed in accordance with the invention. Fig. 2 is a top plan view thereof. Fig. 3 is a horizontal sectional view. Fig. 4 is a longitudinal cross sectional view on the line 4—4 of Fig. 2. Fig. 5 is a similar cross sectional view on the line 5—5 of Fig. 2.

Referring to the drawing, 10 denotes a casing, preferably of cylindrical form, open at both ends and provided at its lower end with depending flanges 11 carrying radially disposed lugs 12. The last-mentioned lugs are so constructed and arranged as to engage bayonet slots 13, formed in the wall of a bottom member 14, so that said bottom member may be removably connected with the lower end of said casing 10. The bottom member 14 is provided with outlet openings 15, as shown, and extended diametrically across said member is a partition or baffle 16, the upper edge of which is preferably of comb-like form, as indicated at 17.

The upper end of the casing 10 is closed by a cover member 18, provided with inlet openings 19, and having a peripheral flange 20, so positioned as to rest upon the upper edge of the casing 10. Depending from said cover 18, and extended axially and downwardly through the casing 10 is a carrier or partition 21, which is of a width to extend diametrically across the

inferior diameter of the casing 10, so as to divide said casing into two vertical chambers. The lower end of said partition 21 is provided with offset lugs 22, which are so disposed as to pass beneath studs 23, projecting inwardly from the wall of the casing 10, so as to normally lock said partition and cover from withdrawal while the device is in operation.

Mounted on the opposite faces of the partition member 21, in such manner as to be wholly supported thereby, are two sets of baffles one of said sets being located in each of the chambers separated by the partition 21. Each set of baffles consists of a plurality of downwardly inclined sector shaped plates 23 and 24 arranged one above the other in staggered relation, and each baffle having a free "overflowing" edge disposed at approximately right angles to the contiguous surface of the partition member 21, so as to overlap in spaced relation at positions in a vertical plane 20 parallel with the longitudinal median line of said partition 21. Each baffle is attached to and extends from a flat surface of the partition 21, and is provided with a second free edge having a curvature complementary to that of casing 10, 25 and rotatably and slidably engaging the inner surface of the latter while the parts are in operative position. The curved edges, while the baffles are in position, are helical in character. The free drip edges of the baffles 24 are of comb-like formation.

In practice, the bottom portion 14 provides a chamber for the storage of an amalgamating medium, such as commercial mercury, said amalgamating medium being separated into two pools 35 by the partition 16. When it is intended to use the device, it is placed within an ordinary type of dental cuspidor, in such manner that all fluids which are deposited into the cuspidor are directed downwardly through the inlet openings 19. From there, the fluids will drop downwardly over the successive baffles 23 and 24, the comb-like edges 25 tending to screen and separate the solids from the liquids, so that as they are washed down they will be deposited in one or the other of the pools of mercury. It will be noted that the partition 16 is normally disposed at right angles to the plane of the partition 21, so that the sets of baffles will direct the downwardly moving substances into the respective pools of mercury. Obviously, the solids will merely drop into the mercury and the fluids will remain on top thereof, the excess fluid flowing outwardly through the openings 15 to the sewer main, or any other point of disposal. After the device has been in opera- 55

tion any desired period, it is removed from the 5 cuspidor and the bottom member 14 may be disengaged from the casing 10, so that the mercury may be poured into a suitable receptacle for subsequent treatment to remove the gold and other 10 precious metals which normally flow through a dental cuspidor. The top 18, together with the partition 21 and the baffles carried thereby may also be removed for such cleansing as may be 15 necessary, and for the removal of any particles of metal which may be caught by the comb-like edges 25. The comb-like edge 17 of the partition 16 also tends to entrap metal particles which might otherwise tend to flow outwardly with 20 the liquids.

The advantages of the invention will be readily understood by those skilled in the art to which the invention belongs. For instance, it will be observed that a very simple form of precious 25 metal trap is provided, so constructed that it may be assembled with any standard type of dental cuspidor. A further advantage is that by reason of the baffling and straining action applied to the fluids as they flow downwardly 30 through the device, a maximum recovery of precious metals is possible, because there is no opportunity for such metals to escape from the device before they are brought into contact with the amalgamating medium. By constructing the 35 device of sections which are readily detached or assembled, ready access to the amalgamated metal is provided, and it is possible to effectually cleanse and sterilize all of the parts of the trap.

Having thus explained the nature of the invention and described an operative manner of 35 constructing and using the same, although without attempting to set forth all of the forms in which it may be made, or all of the forms of its use, what is claimed is:—

40. 1. A precious metal trap for dental cuspidors comprising a casing having a bottom portion constructed and arranged to provide an amalgamating chamber, said chamber having one or more outlet openings, a partition extending diametrically across said chamber between said openings, a closure for the upper end of said casing having one or more inlet openings, a partition extended axially through said casing and diametrically across the same, said partition being normally positioned at right angles to the partition in said amalgamating chamber, and a plurality of staggered inclined baffles supported by said axially disposed partition.

45. 2. A precious metal trap for dental cuspidors comprising a tubular casing, a bottom member constructed and arranged to provide a chamber for an amalgamating medium, said bottom member having one or more outlet openings, a partition in said bottom member extending diametrically across the same between said outlet openings, the upper edge of said partition being of comb-like form, a pin and slot connection between said casing and said bottom member, a closure member for the upper end of said casing having inlet openings therein, a partition secured to and depending from said closure member and extending axially through said casing at approximately right angles to the plane of the first-mentioned partition, said axially disposed 50 partition also extending diametrically across said casing, and a plurality of baffles projecting from said axially disposed partition and arranged in downwardly inclined staggered relation, the alternate baffles being provided with comb-like 55 edges.

3. A precious metal trap for dental cuspidors comprising a casing, an amalgamating chamber engaging the lower end of the casing and having a partition extended across the same in such manner as to divide the amalgamating chamber into separate compartments, there being separate outlets for the respective compartments, a removable partition plate located within said casing and disposed axially therein with its lower end adjacent to the top of said amalgamating chamber, said partition plate being at right angles to the partition in the amalgamating chamber, baffles supported by opposite sides of said partition plate and so positioned as to direct flowable material into the respective compartments of the amalgamating chamber, and a closure member removably engaging the top of the casing and having inlet openings so positioned as to direct inflowing material onto the baffles located on both 20 sides of said partition plate.

4. A precious metal trap for dental cuspidors comprising a casing, an amalgamating chamber removably engaging the lower end of said casing and having one or more outlets therein, a flat partition plate removably supported at its upper 25 end and depending vertically into said casing with its lower end normally positioned adjacent to the top of said amalgamating chamber, sets of baffles respectively carried by said partition plate and extending from the opposite surfaces 30 thereof, each set of baffles consisting of a plurality of downwardly inclined plates arranged one above the other in staggered relation, and each having an overflow edge disposed at approximately right angles to the contiguous surface of said partition plate, so as to overlap in spaced relation at positions in a vertical plane approximately parallel with the longitudinal median line of said partition plate, the free edge 35 of the lowermost baffle of each set being positioned to discharge material into said amalgamating chamber, each baffle also having a free edge touching the inner surface of said casing, said partition plate and said baffles being so connected as to constitute a single unit insertable 40 into and removable from said casing, and means for directing inflowing material onto the topmost baffles.

5. A precious metal trap for dental cuspidors comprising a casing, an amalgamating chamber 45 removably engaging the lower end of said casing and having one or more outlets therein, a partition in said amalgamating chamber extended diametrically across the chamber in such manner as to divide the same into separate compartments, 50 a flat partition plate removably supported at its upper end and depending vertically into said casing with its lower end positioned adjacent to the top of the partition in the amalgamating chamber but at right angles thereto, sets of baffles 55 respectively carried by and extending from opposite surfaces of the partition plate, each set of baffles consisting of a plurality of downwardly inclined plates arranged one above the other in staggered relation, and each having a free overflow edge disposed at approximately right angles to the contiguous surface of the partition plate, so as to overlap in spaced relation at positions in a vertical plane approximately parallel with the longitudinal median line of said partition plate, 60 with the lowermost baffle of each set being positioned to discharge material into a compartment of the amalgamating chamber, each baffle being provided with a second free edge touching the inner surface of said casing while the parts are 65 70 75 80 85 90 95 100

in operative position, said baffles and said partition plate being so connected as to provide a single unit insertable into and removable from said casing, and means for directing inflowing material onto the topmost baffle of each set.

6. A precious metal trap for dental cuspidors comprising a casing, an amalgamating chamber removably engaging the lower end of the casing and having one or more outlets therein, a closure member engaging the top of the casing and having one or more inlet openings so as to direct inflowing material into the casing, a partition plate secured at its upper end to said closure member and depending vertically into said casing with its lower end normally positioned adjacent to the top of the amalgamating chamber, sets of baffles respectively carried by and extending from the opposite surfaces of said partition plate, each set of baffles consisting of a plurality of downwardly inclined plates arranged one above the other in staggered relation and each having a free overflow edge disposed at approximately right angles to the contiguous surface of the partition plate, so as to overlap in spaced relation at positions in a vertical plane approximately parallel with the longitudinal median line of said partition plate, each baffle also having a free edge touching the inner surface of said casing while the baffles are in position within the casing, the uppermost baffles being positioned beneath the openings in said closure and the lowermost baffles being positioned to discharge material into said amalgamating chamber, said closure, said partition plate and said baffles being so connected as to provide a single unitary structure.

7. A precious metal trap for dental cuspidors comprising a casing, an amalgamating chamber removably engaging the lower end of the casing and having one or more outlets therein, a re-

movable partition plate suspended from its upper end and depending vertically into said casing with its lower end normally positioned adjacent to the top of the amalgamating chamber, sector-like baffles extending from the opposite surfaces of said partition plate, said baffles being downwardly inclined and arranged one above the other in staggered relation, and each having a free overflow edge disposed at approximately right angles to the contiguous surface of said partition plate and in overlapping spaced relation, the curved edges of the sectors touching the inner surface of said casing, the lower baffles being positioned to discharge material into said amalgamating chamber, and means for directing inflowing material onto the topmost baffles.

8. A precious metal trap for dental cuspidors comprising a casing, an amalgamating chamber removably engaging the lower end of the casing and having one or more outlets therein, a removable partition plate suspended from its upper end and depending vertically into said casing with its lower end normally positioned adjacent to the top of the amalgamating chamber, sector-like baffles extending from the opposite surfaces of said partition plate, said baffles being downwardly inclined and arranged one above the other in staggered relation, and each having a free overflow edge disposed at approximately right angles to the contiguous surface of said partition plate and in overlapping spaced relation, the curved edges of the sector following approximately helical lines and touching the inner surface of said casing, the lower baffles being positioned to discharge material into said amalgamating chamber, and a cover for said casing having openings therein located immediately above the topmost baffles.
